[57] CLAIM

The ornamental design for a frozen confection, as shown and described.

DESCRIPTION

FIG. 1 is a perspective view showing my new design;

FIG. 2 is a front elevational view thereof;

FIG. 3 is a side elevational view thereof;

FIG. 4 is a back elevational view thereof;

FIG. 5 is a top elevational view thereof;

FIG. 6 is a bottom elevational view thereof;

FIG. 7 is a perspective view of a second embodiment of FIG. 1, the sole difference residing in the contrasting colors; and,

FIG. 8 is a perspective view of a third embodiment of FIG. 1, the sole differences residing in the contrasting colors and the configuration of the stick, which is flat and plain on the sides not shown.

The line patterns shown in the views represent color. A characteristic feature of the design is the presentation of a star on the top surface of the frozen confection, and the points of a star running along the elevational surface thereof, in one color, and the areas filling the interstices between the star's points in a different color or colors.
